Patented Sept. 2, 1913.

UNITED STATES PATENT OFFICE.

FRANK A. McGUIRE, OF IOLA, KANSAS.

CUSPIDOR.

1,072,140.

Specification of Letters Patent. Patented Sept. 2, 1913.

Application filed March 31, 1913. Serial No. 757,941.

To all whom it may concern:

Be it known that I, FRANK A. McGUIRE, a citizen of the United States, residing at Iola, in the county of Allen and State of Kansas, have invented certain new and useful Improvements in Cuspidors; and I do hereby declare the following to be a full, clear, and exact description of the invention, such as will enable others skilled in the art 10 to which it appertains to make and use the same.

This invention comprehends improvements in cuspidors, and relates more particularly to those which are especially 15 adapted for use upon railway cars.

The primary object of the invention resides in the provision of a cuspidor of this type equipped with novel means for opening and closing the same.

20 Another and more specific object of the invention is to provide a car cuspidor having a swinging bottom which carries an angular arm, an upwardly extending rod pivotally connected to the free end of said 25 arm, said rod extending through an opening formed in the car floor, and novel means for locking the arms so that the cuspidor will remain closed.

Another object of the invention is to provide 30 a car cuspidor having a body formed in sections, the upper section being formed with a concavo-convex flange which fits over a bead or flange formed upon the lower section, thereby forming a perfect joint.

35 With these and other objects in view, as will become more apparent as the description proceeds, the invention consists in certain novel features of construction, combination, and arrangement of parts, as will be 40 hereinafter described and claimed.

For a complete understanding of my invention, reference is to be had to the following description and accompanying drawings, in which—

45 Figure 1 is a vertical sectional view, partly in elevation, showing the cuspidor open, Fig. 2 is a similar view, showing the cuspidor closed, Fig. 3 is a detail top plan view, showing the receptacle through which 50 one of the operating rods passes, and also shows a portion of said rod, and, Fig. 4 is an enlarged sectional view taken on the plane of line 4—4 of Fig. 3.

Referring in detail to the drawings by 55 numerals, 5 designates a car floor, which is recessed, as indicated at 6, for the purpose

of supporting a cuspidor, generally designated 7. This cuspidor comprises a frustoconical neck 8, which is formed with an annular flange 10 that extends around the 60 top of the recess 6. The body of the cuspidor comprises an upper section 11 formed upon the neck 8 and a lower section 12, which is connected to the upper section by means of the hinge 13. The upper section 65 11 is formed about its lower edge with a concavo-convex flange 14, which provides a downwardly opening channel for the reception of the bead or flange 15 formed around the upper edge of the section 12. It will be 70 seen that this construction provides a close fitting joint between the two body sections.

The means which I have provided for actuating the lower section 12 so that the contents of the cuspidor may be discharged, 75 include an arm 16 which is bent back upon itself to provide a portion 17, that is secured to the cuspidor, by means of suitable fasteners 18. The arm 16 is preferably formed of a metallic substance, having a slight degree 80 of resiliency to accomplish an object which will be hereinafter set forth. An upwardly extending rod 18 is pivotally connected to the free end of the arm 16, projects through 85 a slot 19 formed in the car floor, and carries adjacent its upper end, a pull ring 20.

A cylindrical cup or receptacle 21 is fitted within a recess formed over and communicating with the slot 19. The bottom 22 of the receptacle is formed with an annular slot 23, 90 having the laterally extending portion 24, adjacent one end thereof. The bottom of the receptacle is also formed with an off-set portion 25, which forms a pocket opening upon the slots 19 and 23. As shown in Fig. 95 3, this off-set portion is formed upon the same side of the slot 23 as the portion 24, but is spaced a considerable distance therefrom. A hinged lid 26 closes the receptacle 21 and lies flush with the top of the floor 5. 100 A lug 27 is formed upon the vertical wall of the receptacle 21, and is adapted to support the pull ring 20, in a horizontal plane. The rod 18 carries near its upper end, a laterally projecting pin 28, which, by engaging the under side of the off-set portion 25, 105 serves to lock the rod 18 against upward movement and thereby maintain the cuspidor sections in close contact.

To swing the body section 12 downwardly 110 so as to empty the contents of the cuspidor, the lid 26 is raised and the pull ring 20

grasped so as to lift the rod 18. Before this can be done, however, it is necessary to depress the same slightly so as to withdraw the pin 28 from the off-set portion 25 and then move the rod along the slot 23 until the pin comes under the portion 24 thereof. In closing the cuspidor, a reverse series of operations is necessary. It will be noted that the spring arm 16 will give sufficiently to permit the pin 28 being easily moved into and out of the pocket formed by the off-set portion 26 and that, furthermore, said pin will hold the cuspidor sections in close contact with each other.

The means above described for opening and closing the cuspidor and the construction of the cuspidor itself, are the features I consider of primary importance in the present application and no claim is made to the sliding cover 29 and the casing 30, said parts being covered in my pending application, filed January 2, 1913, Serial No. 739,865.

It is to be understood that while I have shown and described the preferred embodiment of my invention, I do not wish to be limited to this exact construction, combination, and arrangement of parts, but may make such changes as will fall within the spirit and scope of the invention.

Having thus described my invention, what I claim is:—

1. In combination, a horizontal supporting surface having an opening formed therein, a cuspidor supported under said surface by the walls of the opening and provided with a hinged bottom, a laterally pro-

jecting arm secured to the hinged bottom, an upwardly extending rod pivotally connected to the free end of said arm, the support being slotted and recessed to permit the passage therethrough of the arm, a receptacle fitted within said recess and having an angular slot formed in the bottom thereof, and a laterally projecting pin carried by said rod for engagement with the under side of the receptacle bottom, whereby the rod is locked against upward movement.

2. In combination, a horizontal support formed with an opening extending therethrough, a cuspidor supported below said support for engagement with the walls of the opening, said cuspidor being provided with a hinged bottom section, a resilient arm extending laterally from the bottom of said section, an upwardly projecting rod pivotally connected at its lower end to the free end of said arm, the support being slotted and recessed to permit the passage therethrough of the arm, a receptacle fitted within said recess and having its bottom angularly slotted over said first mentioned slot, said bottom being also formed with an off-set portion to provide a downwardly facing recess, and a laterally projecting pin carried by said rod for engagement with the off-set portion, whereby the rod is locked against upward movement.

In testimony whereof I affix my signature in presence of two witnesses.

FRANK A. McGuire.
